UNITED STATES PATENT OFFICE.

WILLIAM E. COLLIER, OF MUSKEGON, MICHIGAN, ASSIGNOR TO RACINE
BOAT MFG. CO., OF MUSKEGON, MICHIGAN, A CORPORATION OF
MICHIGAN.

POWER TRANSMISSION FOR EXPLOSIVE-MOTOR-DRIVEN BOATS.

No. 821,925.

Specification of Letters Patent.

Patented May 29, 1906.

Application filed September 16, 1904. Serial No. 224,685.

To all whom it may concern:

Be it known that I, WILLIAM E. COLLIER, of Muskegon, in the county of Muskegon and State of Michigan, have invented certain new and useful Improvements in Power Transmission for Explosive-Motor-Driven Boats; and I do hereby declare that the following is a full, clear, and exact description thereof, reference being had to the accompanying drawings, and to the letters of reference marked thereon, which form a part of this specification.

This invention relates to improvements in explosive-engine-driven boats, and refers more specifically to a driving mechanism embracing a propeller having angularly-adjustable and reversible propeller-blades and an explosive-engine applied to drive the propeller and provided with a valve mechanism for controlling the supply of explosive admixture to the engine and ignition mechanism which is adjustable to change the sparking period in unison with the adjustment of the valve mechanism.

In a propelling mechanism embodying my invention the propeller-wheel for the boat comprises blades which are controllably rotative in the hub of the propeller-shaft, whereby the pitch of the blades may be varied either way from a plane passing perpendicularly through the axis of the propeller-shaft, such variations of the pitch placing the blades in a neutral or intermediate position or in position for driving the boat forwardly or astern at any speed desired within the limits of its speed. The explosive-engine embraces a valve mechanism for controlling the supply of explosive mixture to the engine, mechanism for controlling the sparking period of the ignition mechanism, and a single manually-operable part or hand-lever having operative connection with the propeller-blades and also with the valve mechanism and the devices for controlling the sparking period, in such manner that the adjustment of these parts is effected in unison and the ratio of the power of the engine to the load on the propeller-wheel will remain substantially constant under varying loads on the propeller-wheel resulting from adjustment of the propeller-blades to their neutral or intermediate position or at varying angles for driving the boat

either forward or backward at varying speeds.

As a result of the construction described if the blades of the propeller-wheel be adjusted to drive the boat in either direction at a given speed the engine controlling or adjusting mechanism is operated in unison with the propeller-controlling mechanism in such manner that the ratio of the power of the engine to the increased load on the propeller-wheel remains constant and the same as that between the power of the engine and the load representing the work required to turn the crank-shaft of the engine when the propeller-blades are in their inactive or non-propelling position. Between this low extreme of load and that corresponding to the highest efficiency of the engine the ratio of the power of the engine to the load on the propeller does not vary, so there can be no racing of the engine when the load is suddenly dropped by shifting the pitch of the propeller-blades toward the neutral position thereof, nor is there any liability of sudden strains being brought on the engine when the load is suddenly increased by increasing the pitch of the blades. The proper relation of the power of the engine to the load on the propeller-wheel may therefore be maintained by one not experienced in the handling of crafts of this nature, as it is only necessary to operate the single manually-operable part or lever and the operator need not separately watch the engine and propeller to prevent the propeller from racing or to prevent the load coming too suddenly on the engine.

In the drawings are shown one embodiment of my invention which has been thus generally set forth; but it is to be understood that the structural details, which are hereinafter described, may be widely varied without departing from the spirit or scope of the invention. Inasmuch, however, as such certain of the structural details possess practical merit, they are hereinafter made the subject of specific claims.

In the drawings, Figure 1 illustrates in side elevation a boat or launch astern, showing the rudder and propeller and being broken away to show the explosive-engine which furnishes power to propel it. Fig. 2 is an enlarged partial horizontal sectional and partial

plan view of the engine, showing the sparking mechanism and the means for coupling the engine-shaft to the propeller-shaft, taken on line 22 of Fig. 1. Fig. 3 is a detail section of the coupling-sleeve for coupling the engine and propeller shafts, showing said shafts therein. Fig. 4 is a fragmentary vertical section taken through the make-and-break device of the sparking mechanism. Fig. 15 5 is an enlarged fragmentary detail showing the make-and-break device of the sparking mechanism, the cam for adjusting the same, and the connection between said parts and the valve-controlling rod. Fig. 6 is a longitudinal section taken through the propeller-hub and the bearings and stuffing-box for the propeller-shaft. Fig. 7 is a side elevation of said parts of the propeller-hub and blades, being separated from each other to more 20 clearly show the construction of the individual parts. Fig. 8 illustrates the rear end of the propeller-shaft, showing its cross-head and the manner of attaching the blades to said cross-head. Fig. 9 is a section taken 25 through the propeller-hub, showing the blades and other parts in elevation.

The engine herein shown and the mechanism for controlling its operation is the same as that illustrated in my copending application for United States Letters Patent, filed concurrently herewith, Serial No. 224,686; but its controlling mechanism is briefly explained herein in order that the unison operation of the parts may be understood from the 35 herein-contained description.

As herein shown, D designates the rear or stern of a typical form of launch, and D' the rudder thereof.

A designates the cylinder of an explosive-40 engine located at the stern of the launch or boat; B, its crank-shaft, and B' the balance-wheel of the crank-shaft.

C designates as a whole the propeller-wheel of the boat, and C' the propeller-shaft, which 45 is coupled to the crank-shaft of the engine. The engine shown is a two-cycle engine or one in which an explosion takes place in each rotation of the crank-shaft, and the explosive mixture is drawn from the carbureter A² 50 through the inlet-valve A³ into a compression-chamber located in the crank-chamber of the engine, whereby the charge of explosive mixture is compressed during the instroke of the piston and is directed into the cylinder at the 55 termination of said instroke and compressed in the cylinder during the outstroke of the piston and subsequently ignited to produce the power-stroke. The inlet-valve A³ is so arranged and constructed that it will in no 60 instance entirely cut off the supply of fuel or explosive mixture to the engine-cylinder. Inasmuch as such details of the engine are familiar, a further showing or description thereof is unnecessary. The inlet-valve is 65 provided with a rotative stem A⁴, projecting

laterally therefrom. The exhaust-valve of the engine (not shown) discharges through a muffler A⁵, which latter discharges outside of the boat.

A⁶ designates the casing of a rotary pump 70 located at the base of the crank-chamber, and the rotative shaft a of said pump is shown as provided with a gear-wheel a', which meshes with a gear-wheel a² on the crank-shaft, whereby said pump is driven.

A' designates a pipe leading from the pump-chamber to the water-jacket of the cylinder.

The ignition mechanism is of that class known as the "three-wire" system, embracing a battery or other source of electrical energy and an induction-coil. One wire e leads from the secondary coil of the induction-coil and is attached to a binding-screw forming part of or connected with an arcing-plug a³ at the outer end of the cylinder. A second wire e' leads from the primary coil and is attached to a binding-screw e², insulated from the engine-frame and constituting the stationary part of the make-and-break device, and a wire e¹², grounded to the engine-frame 90 and constituting the return-wires of both the primary and secondary circuits. The binding-screw e² is fixed on a ring E' concentric with the crank-shaft and which has a limited rotative movement on a boss a⁴, surrounding 95 the crank-shaft and projecting laterally from the crank-chamber. Said ring is held from endwise movement on said boss by a pin a⁶, which engages a curved guide-groove in the ring. Said binding-screw has contact with 100 a bar e⁴, that is fixed to a flange or lug at the top of the ring, it being fastened to an insulating-block e⁵, which is attached thereto by bolts e⁶. The other member of the make-and-break device consists of a shouldered spring-pressed pin e⁷, which is located in a correspondingly-shouldered transverse opening in the crank-shaft in line with the inner end of 105 said bar e⁴, which inner end of which bar extends toward the shaft and contacts with the pin e⁷ during each rotation of the shaft in a manner to close the primary circuit of the igniting mechanism. The pin e⁷ is held with its reduced end projecting from the cylindric surface of the shaft by means of a spiral 110 spring e⁸, interposed between the larger end of the pin and a screw-plug e⁹, which has screw-threaded engagement with the larger end of the shaft-opening, said spring permitting the pin to be depressed when struck by 115 the bar e⁴. The ring E', having a limited rotative or angular movement on the boss a⁴, may be angularly shifted or displaced to vary 120 the sparking period of the sparking mechanism relatively to the stroke of the engine-piston, and this is accomplished by mechanism now to be described, which mechanism also operates in unison the valve mechanism to 125 control the admission of the explosive charge to the engine-cylinder.

F designates a coupling-sleeve which couples together the crank and propeller shafts, which latter are shown as in axial alignment. Said sleeve is free to slide endwise on the crank-shaft, but is non-rotatively secured thereon by means of a spline f or otherwise. The coupling-sleeve is also splined to the propeller-shaft, so that said shaft rotates with the engine-shaft and is also fastened thereto, as by a set-screw f' , to prevent relative endwise movement of the propeller-shaft and sleeve and causes the propeller-shaft to slide endwise with said sleeve. Said coupling-sleeve is operatively connected with the ring E', so that when the sleeve is shifted endwise of the crank-shaft the ring is rocked on its bearing, and said rocking ring is so connected with the rocking stem A⁴ of the inlet-valve that the ring and stem are rocked in unison. The coupling-sleeve is shifted endwise of the crank-shaft by the following device:

G designates a split collar surrounding and located in an annular recess in the coupling-sleeve F, so that said coupling-sleeve may rotate freely thereon. G' designates a vertically-reciprocating lever, which is forked at its lower end, the fork-arms g extending on either side of the collar and being pivoted at their lower ends by a bolt g' to a link g^2 , which latter is in turn pivoted at its other end to the engine-frame by a bolt g^3 . Said link g^2 is made wide to constitute a pan to catch oil which may drop thereon from the parts above. The arms g of said lever G' are pivoted to the opposite sides of the collar G by means of screw-studs g^4 , Fig. 2. The said lever G' is adapted to be locked in any adjusted position to a curved guide G⁵, Fig. 1, which is herein shown as fixed to the muffler. Said lever is fixed in any adjusted position to the guide by means of a screw g^5 . The mechanism for communicating motion from said sliding coupling-sleeve to the ring E' of the make-and-break device of the igniting mechanism in a manner to rock said ring relatively to the crank-shaft and for also communicating motion to rock the stem A⁴ of the inlet-valve is made as follows: The collar G on said sliding coupling E is provided with a horizontal guide-arm G⁴, that extends toward the engine-frame and parallel with the axis of the crank-shaft and has guiding engagement at its inner end or that adjacent to the engine-frame with a stud g^7 , projecting laterally from the engine-frame and entering an axial guide-socket in said arm. Said arm G⁴ is provided on its side remote from the crank-shaft, as herein shown, with a generally V-shaped cam-groove G⁵. G⁶, Figs. 2 and 3, designates a vertically-swinging lever provided at one end with a bearing-sleeve g^8 , which has rocking engagement with a stud g^9 , that projects laterally from the engine-frame. Formed on said

sleeve g^8 is a downwardly-extending arm g^9 , provided at its lower end with a friction-roller g^{10} , that engages the cam-groove G⁵ of the arm G⁴ of the endwise-movable collar G. Said lever G⁶ extends transversely over the crank-shaft and is pivotally connected at its free end to the lower end of a connecting rod or link H, Figs. 1 and 5, the upper end of which latter is pivotally connected with the rocking stem A⁴ of the inlet-valve, as shown in my copending application, in such manner that when the rod H is raised or depressed said valve-stem rocks, and thus opens or closes the valve. Said lever G⁶ is also pivotally connected at its free end with a short link G', that is loosely connected at its lower end with a rigid radially-extending arm or lug E² on the ring E'. With this construction it will be observed that when the lever G' is swung toward or from the engine the coupling-sleeve F is moved longitudinally of the crank-shaft, carrying with it not only the propeller-shaft, but the cam-grooved arm G⁴ of the collar G, which arm operates through the medium of the arm g^9 of the lever G⁶ to swing said lever vertically, and such movement of the lever G⁶ transmits a rocking motion to the ring E' on its supporting-boss, whereby the bar g^1 of the make-and-break device is shifted angularly on the boss relatively to the coöperating spring-pressed pin g^2 of said device, thereby varying the sparking period of the ignition mechanism relative to the piston-stroke of the engine. The same movement of the lever G⁶ acts to shift endwise the connecting rod or link H and, through the rocking stem A⁴ of the inlet-valve, to angularly shift said inlet-valve. The central or intermediate position of the parts is the position when the antifriction-roller g^{10} of the arm g^9 of the lever G⁶ occupies the apex of the V-shaped groove of the arm G⁴, and at this time the lever G' occupies the intermediate part of its throw. When the parts are in these positions, only sufficient explosive mixture is admitted to the cylinder to furnish power to turn the piston over with no load thereon, but that required to overcome the friction of the piston and associated parts and also for rotating the propeller and its shaft when the propeller is in its non-propelling adjustment. Movement of the lever G' in either direction acts, through said cam-actuated mechanism, described, with a like effect on the sparking mechanism and the valve-controlling mechanism—that is, to produce a sparking earlier in the stroke of the piston and to admit a greater volume of the explosive mixture to the cylinder—and the maximum volume of the explosive mixture is admitted to the cylinder and the sparking occurs earliest in the power-stroke of the piston when the roller of the arm g^9 of the lever G⁶ occupies one end of said cam-slot. It will be understood that the direction toward which the lever G' is

thrown from its central position determines the direction of movement of the boat—that is to say, when the lever is swung in one direction the boat moves forwardly and when 5 swung in the other direction the boat moves rearwardly.

With respect to the action of the lever G' on a propelling-wheel of the kind herein shown, wherein the direction of the propulsive power is determined by the relation of the pitch of the blades to a plane passed perpendicularly through the axis of the propeller-shaft, it may be preliminarily stated that when the lever G' occupies a central position 10 the propeller-blades are in their non-propelling or parallel positions and that when said lever is shifted one way or the other from its central position the pitch of the blades is varied either to drive the boat ahead or to reverse it. The adjustment of the parts is such, as before stated, that the ratio of the power of the engine to the load on the propeller-wheel is maintained constant throughout 15 all of the movements of the regulating mechanism.

The means whereby the pitch of the blades of the propeller-wheel is varied through operation of the lever G' (which, as before stated, regulates in unison the sparking period of the ignition mechanism and the position of the valve mechanism of the engine) embraces, in connection with the endwise-movable propeller-shaft, means for connecting the propeller-shaft with the blades, 20 whereby such endwise movement of the shaft acts to vary the pitch of said blades.

Referring now to the construction of the propeller, its relation to the propeller-shaft, and the manner of its operation by the lever 25 G', said parts are made as follows:

I, Figs. 6, 7, and 9, designates as a whole the propeller-hub, and I' designates the bearing for the hub, which has bearing in a sleeve I², which is attached to the stern of the boat 30 and extending rearwardly therefrom. Said bearing-sleeve is longitudinally divided into two parts that are joined by bolts i passing through lugs at the sides of said parts. One of said parts is provided at its forward end 35 with a radial annular flange i', which is fastened to the stern of the boat by screws or like fastening means. The other part of said bearing-sleeve is provided at its front end with a lug or flange i², that fits flat against the rear face of the flange i' and is attached 40 thereto by a screw-bolt i³, said bolts i³ and i constituting the means by which the upper part of the divided sleeve is fixed to the lower part thereof. Said flanged part is provided 45 with a boss I⁴, that extends into the dead-wood of the boat. The bearing portion I' of the hub is provided with a plurality of exterior annular rings or ribs I⁴, that engage complementary internal grooves in the sleeve, 50 thereby constituting a thrust-bearing which

takes the endwise thrust of the propeller-hub and relieves the propeller-shaft of such thrust. The internal annular grooves in the sleeve, within which fit the annular rings or ribs of the hub-bearing, are formed, as herein 55 shown, in a suitable annular packing made separate from and fitted within said sleeve. The propeller-shaft is keyed to the bearing of the propeller-hub, Fig. 6, so as to transmit a rotary motion thereto, while permitting the 60 shaft to slide endwise in said hub. The hub is made in two parts, it being transversely divided in a plane perpendicular to the longitudinal axis thereof and fastened together by bolts i⁵, as shown in Figs. 7 and 9. The 65 meeting faces of the two parts of the hub are each provided with diametrically-opposed half-cylindric sockets or depressions i⁶, said depressions constituting when the parts are fastened together cylindric bearing-apertures 70 for the shanks j of the blades J of the propeller-wheel, said blades when in position in the hub extending in opposite directions therefrom. The bearings j of said blades are provided at their inner ends with rigid radial 75 arms j', and the hub is chambered to receive said arms and to permit angular movement thereof. The rear end of the propeller-shaft extends rearwardly into said chamber of the hub and is provided with oppositely-extending lugs c c, which are provided at their outer 80 ends with pins c' c', the pin of one lug c extending in a direction opposite to that of the pin of the other lug. The arms j' of the blade-bearings are slotted and pass over said 85 pins c', whereby endwise movement of the shaft relatively to the hub has the effect of rotating said blades, and thereby changing the pitch thereof. The central position of the shaft relative to its endwise movement 90 shifts the blades into their central or non-propelling position, and the shifting of the shaft endwise in either direction has the effect to vary the pitch of the blades, the extent of variation of the pitch of the blades 95 and the direction of the pitch depending upon the extent and direction of movement of the shaft as controlled by the lever G'. 100

A pipe or tube K surrounds the inner end of the propeller-shaft and fits within and has screw-threaded engagement with the boss of the flange of the thrust-bearing sleeve. Said pipe extends through the dead-wood of the boat into the interior thereof and has screw-threaded engagement at its other end with a 105 collar K', which surrounds the propeller-shaft and constitutes a part or member of a stuffing-box. The other means of the stuffing-box consists of a hollow exteriorly-screw-threaded nut K², which surrounds the 110 shaft and fits within and has screw-threaded engagement with the said collar. A packing k is inserted between the inner end of said 115 nut and an interior shoulder of the collar, the whole constituting a stuffing-box within the 120

interior of the boat, which prevents the entrance of water to the boat.

An important result or advantage is obtained by the employment of the features of construction hereinbefore described, for the reason that the adjustable and reversible propeller-blades may be thrown into their neutral or inert positions or into position to drive the boat either rearwardly or forwardly by the movement of a single manually-operable part and without stopping the engine, or changing the speed thereof, while at the same time the admission-valve of the engine and the sparking devices thereof are adjusted in unison with the adjustment of the blades to vary the fuel-supply to the engine and the sparking period thereof in accordance with the work to be done or the load upon the propeller. The fuel-supply and sparking period of the engine may thus be maintained constantly in such relation as to produce the best results in the operation of the engine, and at the same time the position and driving force or effect of the blades and the fuel-supply and sparking period may be maintained in uniform relation under varying degrees of speed in the boat either when advancing or backing or when the propeller-blades are in their neutral position and the boat is not advancing in either direction.

I claim as my invention—

1. A propelling mechanism for boats comprising an explosive-engine, its crank-shaft, a valve mechanism for controlling the supply of explosive admixture to the engine, an electric ignition mechanism provided with a member which is adjustable to change the sparking period, a propeller-wheel provided with blades which are angularly adjustable to vary the pitch thereof, an endwise-movable propeller-shaft connected with the propeller-blades and acting by its endwise movement to change the pitch of said blades, a movable cam-plate, operative connections between said cam-plate and said propeller-shaft, producing shifting movement of said cam-plate in the endwise movement of said propeller-shaft, and operative connections between said cam-plate, the valve mechanism and the adjustable member of the ignition mechanism, whereby the propeller-blades, the valve mechanism and the ignition mechanism are adjusted in unison.

2. A propelling mechanism for boats comprising an explosive-engine, its crank-shaft, a valve mechanism for controlling the supply of explosive admixture to the engine, an electric ignition mechanism provided with a member which is adjustable to change the sparking period, a propeller-wheel provided with blades which are angularly adjustable to vary the pitch thereof, an endwise-movable propeller-shaft connected with the propeller-blades and acting, by its endwise movement, to change the pitch of said blades,

a cam-plate movable in a direction endwise of the shaft, operative connections between the said cam-plate and the crank-shaft producing movement of said cam-plate with the crank-shaft in the endwise movement of the latter, and operative connections between said cam-plate, the valve mechanism and the adjustable member of the ignition mechanism, whereby the propeller-blades, the valve mechanism and the ignition mechanism are adjusted in unison.

3. A propelling mechanism for boats comprising an explosive-engine, its crank-shaft, a valve mechanism for controlling the supply of explosive admixture to the engine, an electric ignition mechanism provided with a member which is adjustable to change the sparking period, a propeller-wheel provided with propeller-blades adapted for angular adjustment to vary the pitch thereof, an endwise-movable propeller-shaft connected with the propeller-blades and acting by its endwise movement to change the pitch of said blades, a coupling-sleeve attached to the said propeller-shaft and having sliding connection with the crank-shaft of the engine but rotating therewith, a non-rotative collar engaging said coupling-sleeve, a cam-plate attached to said collar and moving therewith in a direction endwise of the crank-shaft, a hand-lever connected with said non-rotative collar and operative connections between the said cam-plate, the said valve mechanism and the adjustable member of the ignition mechanism, whereby the propeller-blades, said valve mechanism and the ignition mechanism are adjusted in unison.

4. A propelling mechanism comprising an explosive-engine, its crank-shaft, a valve mechanism controlling the supply of explosive admixture to the engine, an electric ignition mechanism embracing a member which is carried by the crank-shaft, and a member which is adjustable to vary the sparking period, a propeller-wheel provided with propeller-blades which are angularly adjustable to vary the pitch thereof, an endwise-movable propeller-shaft connected with the propeller-blades and acting by its endwise movement to change the pitch of said blades, a coupling-sleeve attached to the propeller-shaft and having sliding connection with the crank-shaft of the engine but rotating therewith, a non-rotative sleeve or collar engaged with said coupling-sleeve, a hand-lever connected with said collar, and operative connections between said collar, the valve mechanism of the engine and the adjustable member of the ignition mechanism, whereby said propeller-blades, the valve mechanism and the ignition mechanism are adjustable in unison.

5. A propelling mechanism for boats comprising an explosive-engine, its crank-shaft, a valve mechanism for controlling the supply of explosive admixture to the engine, ignition

mechanism embracing a member which is carried by the crank-shaft, and a member which is adjustable to vary the sparking period, a propeller-wheel provided with propeller-blades which are angularly adjustable to vary the pitch thereof, an endwise-movable propeller-shaft connected with the said blades, and acting by its endwise movement to change the pitch of said blades, a coupling-sleeve attached to said propeller-shaft and having endwise sliding connection with said crank-shaft but rotating therewith, a non-rotative collar engaged with said coupling-sleeve, a cam-plate attached to said collar and movable therewith in a direction endwise of the crank-shaft, a hand-lever connected

with said collar for giving endwise movement to said sleeve, and operative connections between said cam-plate, the valve mechanism of the engine and the adjustable member of the ignition mechanism, whereby the propeller-blades, the valve mechanism and the ignition mechanism are adjusted in unison. 20

In testimony that I claim the foregoing as my invention I affix my signature, in presence 25 of two witnesses, this 6th day of September, A. D. 1904.

WILLIAM E. COLLIER.
